UNITED STATES PATENT OFFICE.

GEORGE L. FULK, OF CLEVELAND, OHIO, ASSIGNOR TO THE POSTAL SUPPLY & MANUFACTURING COMPANY.

PRINTING-MACHINE.

,1,282,211.

Specification of Letters Patent. Patented Oct. 22, 1918.

Application filed April 5, 1916. Serial No. 88,999.

To all whom it may concern:

Be it known that I, GEORGE L. FULK, a citizen of the United States, residing at Cleveland, in the county of Cuyahoga and State of Ohio, have invented a certain new and useful Improvement in Printing-Machines, of which the following is a full, clear, and exact description.

This invention relates to printing mechanism in which there are arranged a plurality of printing instrumentalities which print in prearranged sequence and relative position to form a group of lines of printed matter and indefinitely repeat the impressions of the groups of lines upon a strip of suitable material which is moved and is severed between each group of lines, thereby forming slips.

In another aspect the invention provides an improved printing mechanism having distinct instrumentalities for the printing of constantly recurring matter or unvarying matter, and constantly changing or variable matter in definite relation at each impression of the printing instrumentalities.

The object of the invention is to provide a machine as above referred to, wherein the instrumentalities used and their arrangement and manner of coöperation are such as to permit very rapid printing.

Reference should be had to the accompanying drawings forming a part of this specification, in which Figure 1 is a side elevation of a portion of a machine embodying my invention; Fig. 2 is a top plan view of a machine embodying my invention; Fig. 3 is an end elevation of the machine; Fig. 4 is a sectional elevation showing a portion of the mechanism of the machine; Fig. 5 is a section showing a detail of construction; Fig. 6 is a side elevation of the showing in Fig. 5; Fig. 7 is a longitudinal section of a portion of the machine; Fig. 8 is a top plan view of a part shown in Fig. 7; Fig. 9 is a transverse section on the line 9—9 of Fig. 8; Fig. 10 is a slip such as used in my machine in unfolded condition; Fig. 11 shows an enlarged view of a folded slip; Fig. 12 shows the reverse side of a folded slip.

There are certain classes of printed matter which involve the production of a series of slips of printed matter in which the matter upon each slip is different in part at least from the matter which occurs upon

the other slips. Among such slips may be mentioned theater tickets, in which, when printing a set bearing a given date, each ticket must also have a different row designation and seat designation upon it; or, if the tickets be printed for a complete season, each ticket must vary in row designation and number designation and then the tickets must vary with respect to the dating.

The foregoing illustration will serve to designate a type of this class of printing which is more or less familiar, but there is another example of this type of printing which is perhaps not so familiar, viz: the printing of slips which are used by postal clerks to be inserted in a holder carried by each mail pouch, which slip must contain certain data required by the post office rules to be placed on the slip, among which items required to be on the slip are the place to which the pouch is destined, the place from which the pouch has come, and frequently in this connection the number of the train upon which the pouch is made up. Further, the date upon which the sack is made up must be given and the name of the clerk who has prepared the pouch.

It will be understood that a clerk, on making a run on a given day, will be required to prepare pouches for a number of different destinations. Consequently, in printing these slips, bearing a single date, each slip will contain constantly recurring matter, to-wit: the date, the name and place from which the pouch comes, and also each slip will in turn bear a legend different from all the others, to-wit: the place to which the sack is destined to go.

In printing these slips it is convenient to simultaneously print a plurality of runs, that is to say, to make up the necessary slips for a number of different runs which occur on different dates, and the machine of this invention is more particularly designed to print slips of the character just described, although its organization is such that it can be utilized to print other forms of slips where, on each slip, there is matter which is recurring and matter which is changing upon successive slips.

It should be borne in mind, also, that such slips, as postal slips and theater tickets and other similar printed matter, must be printed at the lowest cost possible, because the use to which they are put is such that the

cost of producing them must be low. The machine of the present invention should, therefore, be considered in the light of the foregoing remarks, bearing in mind that a 5 machine of the type herein described may be run at very rapid speed and thus produce a large number of printed slips with a minimum amount of supervision of the machine.

In the machine as shown in the drawings, 10 there are two side members, 1 and 2, which extend longitudinally throughout the length of the machine. These side members 1 and 2 are held in spaced relationship to each other by retaining members, one of which is 15 shown at 3, which extend transversely of the machine and are secured to the side members. At the end the side members 1 and 2 are mounted upon supports 4, there being a support at each end of the machine and 20 other supports intermediate of the ends, as may be necessary.

In the machine as herein described, there is a mechanism generally represented at A, 25 which prints variable matter. There is a printing mechanism indicated at B which prints constantly recurring matter. There is a mechanism generally represented at C which prints constantly recurring matter which may be changed automatically to 30 change the constant matter printed, as will be later explained.

The mechanism for printing the constantly varying matter is generally represented at A and comprises a member 20 35 which is in the nature of a drum having a surface which is polygonal in nature. The surface just referred to lies between flanges 21 and 22, as will be later explained. The member 20 is mounted upon a shaft 20^a 40 and is suitably driven in a manner which will be subsequently described. Coöperating with the member 20 is a chain of plates, each of the plates being pivotally secured together, the chain of plates being generally 45 represented at 23, and the chain of plates 23 is at their rear end mounted to pass over a drum which is similar to the drum 20. This drum is not shown in the drawings for its construction and operation will be 50 obvious. Of course, the chain 23 may be made up of as many plates as are necessary to print the variable matter upon the slips. The chain of plates 23 will be supported and run in a channel member 24 throughout 55 the greater part of its length, and at the lower portion of the machine the chain of plates will run in a channel member 25. It will thus be seen that the weight of the chain is supported largely by the channels 60 24 and 25 and not by the drums. The plates composing the chain 23 are shown in more detail in Figs. 7, 8 and 9. Each link of the chain comprises a recessed member 23 and within the recessed portion there may 65 be placed printing characters such as slugs

as indicated at 27. These slugs may be held in place by a spring-pressed member 28. Of course, the matter contained upon each slug in the succeeding portions 26 of a chain will vary and the slugs may be removed and 70 replaced with slugs having other printed matter thereon.

As the plates 28 pass over the drum 20 each plate will coöperate with one of the angular surfaces carried by the member 20 75 and the width between the flanges 21 and 22, as well as the peripheral width of a surface of the member 20, is such as to properly accommodate one of the plates of the chain 23. The chain of plates, as it 80 passes from the roller 20, passes between a pair of oppositely disposed rollers 29 which are carried upon shafts 30 and 31 and are operated by meshing gears 32 33. The slugs carried by the plates for the chain of plates 85 23 will be beneath the upper roller 29 and will engage with the strip of paper running through the machine and print thereon.

The gear 32 meshes with a gear 35 which in turn meshes with a gear 34 which is upon the shaft 21^a which, as will be understood, is the same shaft as that carrying the drum 20. Therefore it will be seen that these various instrumentalities are geared so as to run in harmony. The gear 34 is in mesh 90 with the gear 36 which in turn meshes with a gear 37 carried by the shaft 38. This shaft extends transversely of the machine and has secured to it one part of a clutch mechanism 39.

The clutch part 39 is operated by a lever 40 which is suitably connected to a handle 41 which extends adjacent the forward part of the machine and in convenient position to be grasped by the operator.

The part 39^a of the clutch is loose upon the shaft 38 and is either integral with or suitably connected with a gear 42 which gear through suitable gearing drives another gear 43 which is upon the shaft 44. Upon the 110 shaft 44 there is a printing drum 45 which coöperates with a platen 46. The printing drum 45 and the platen 46 form a printing instrumentality which I have generally designated at B. The printing cylinder 45 115 usually is adapted to carry printing characters which when printing a postal slip designate the place from which the pouch has come, that is to say, the train or post office from which the mail matter within the pouch 120 has come.

Upon a shaft 47 there is a gear 48 which by means of suitable gearing 49 communicates with the gear 43. Upon the shaft 47 there is an annular drum member 50 which 125 forms a platen, and below the platen 50 there is a printing instrumentality which coöperates with the platen and which I will now proceed to describe.

The construction is more clearly shown in 130

- Fig. 4. In a suitable upright 51 there is journaled a shaft 52. This shaft carries a gear 48^a which meshes with the gear 48 and forms a driving connection for the shaft 52.
- 5 At the outer end of the shaft 52 there is carried a printing impression member 53. This element is keyed or otherwise secured upon the shaft 52 so that it will be turned by the shaft.
- 10 The shaft 52 is hollow and through it there extends a rod 52^a which at its end is provided with a head 52^b. This head is in alinement and in front of the end of hollow-shaft 52. The rod is jointed as indicated at 52^d and the joint is such that the part of the rod connected with the head cannot rotate with respect to the rest of the rod 52^a. The rod 52^a extends beyond the shaft 52 and is held at its outer end in a convenient manner as suggested at 52^c in Fig. 4, the head 52^b is provided with a depressed portion. The rod 52^a is spring pressed inwardly by a spring 52^e and the rod 52^a is prevented from turning by any suitable means, as by a loop 52^f which is secured to the shaft and engages the base of the machine.
- 15 There extends in alinement with the shaft 52 a reciprocating shaft 54. This shaft at its outer end is provided with a reduced neck portion 54^b and is adapted to receive a printing impression member 55. The printing element is not secured to the shaft 54 but extends through a suitable opening in the impression member 55. The printing element 55 carries a pin 56 and the impression member 53 carries a pin or stop 57. When, therefore, the impression member 53 turns as the shaft 52 is turned the pins 56 and 57 will engage each other and will definitely position the impression members 53 and 55 with respect to each other and the engagement will also cause the driving of the impression member 55.
- 20 The shaft 54 is adapted to be reciprocated at suitable intervals and as it is reciprocated away from the shaft 52, the impression member 55 will be engaged by a pivoted stop member or gate 58 which will cause the impression member 55 to be pushed off the neck 54^b and dropped into a chute 59. As the shaft 54 reciprocates further it comes beneath a chute 60 which is provided with an inner channel of suitable form to receive impression member 55 which may be fed through the chute and which are intended to be successively fed onto the shaft 54 and to operate in connection with the impression member 53.
- 25 The lower part of the chute 60 is closed by a slide 61 which in turn is operated by the shaft 54. There is a pin 62 which extends from the plate 61 and extends into a slot 63 formed in the shaft 54. This pin 62 is adapted to strike against the end of the
- slot 63 at proper time to withdraw the slide 61 so that it will fall in front of the shaft 54 when the shaft 54 is reciprocated to its most outward position. The slide is connected to a pin 65 by means of a pivoted lever 66. The pin 65 will be moved in a direction opposite to the slide 61. Therefore when the slide 61 moves to uncover the lower end of the chute the pin 65 will move in to hold the impression member which is above the lowermost printing element from descending, so that when the slide 61 uncovers the lower end of the chute only one impression member can be removed. When the slide 61 again covers the end of the chute 30 60 the pin 65 is withdrawn and allows the printing element which has been held, to descend to the lower end of the chute and in position to be subsequently fed from the chute. Clearly the chute 60 may be constructed to contain as many printing impression members as may be desired.
- 35 The stop member 58 is pivoted and when there is a printing element taken up by the end of the shaft 54 as it is fed from the chute 90 60, the forward movement of the shaft 54 toward the printing element 53 is not hindered by the member 58 as it may be pushed out by the shaft and the impression member carried thereby.
- 40 As the shaft 54 is reciprocated away from printing position, the rod 52^a and head 52^b move with the shaft, being moved by spring 52^e. The rod 52^a moves until the loop 52^f engages with the gear 48, at this time the 100 head 52^b stops so as to leave sufficient space between the head 52^b and the gate 58 for the impression member which is supported upon the end of shaft 54, to drop, as the impression member is moved off of the shaft, by 105 the engagement of the impression member with gate 58.
- 45 When the shaft 54 moves toward printing position after taking up a new impression member and the gate 58 is engaged and 110 moved to permit the new impression member to pass, there may be a tendency for the impression member to tip, but this is relieved by the engagement of the end of shaft 54 with the head 52^b which of course prevents the new impression member leaving shaft 54. The continued movement of shaft 54, causes the head 52^b and rod 52^a to move, and compresses the spring 52^e.
- 50 The shaft 54 may be reciprocated in any 120 desired manner and as a convenient means of accomplishing this I have devised the following mechanism:
- 55 To the shaft 54 is pivoted a member 70 and to this member 70 there is pivoted a lever 71 which lever 71 as is shown in Fig. 1 is pivoted to an arm 72. The arm 72 is pivoted to a crank 73 which is carried upon one face of a gear 74. The gear 74 is preferably a bevel gear and meshes with a bevel gear 75 130

which is carried upon a shaft that also carries a large wheel 76. The wheel 76 has a belt 77 running over it and this belt also runs around a wheel 78 journaled upon a shaft 79 which shaft is supported on an arm 80 carried by the main frame of the machine. The shaft 79 has a gear 81 upon it which meshes with a gear 82, the last mentioned gear being mounted upon the shaft 54. The belt 77 is rather loose and is held taut and in contact with the pulleys 78 and 76 by means of a belt tightener which comprises a roller 82 carried upon a pivoted arm 83. To the arm 83 there is secured a weight 84. This weight causes pressure upon the belt 77 through the wheel or roller 82. This arrangement causes the belt 77 to be driven and when the wheel 76 is free to move will drive the wheel. However, the wheel 76 is held against rotation. The arrangement is such that the belt 77 may be driven, but will slip on the wheel 76.

In the face of the gear 74 there is a detent with which a latch 86 is adapted to engage. This latch is supported in a sleeve 87 which sleeve is in turn supported by a bracket 88 carried by a part of the main frame of the machine. The latch is urged by a spring 89 in a direction to throw the latch toward the gear 74. The latch is withdrawn from engagement with the gear 74 by means of a lever 90 upon which lever is pivotally supported an armature 91 which is in position to coöperate with an electro-magnet 92.

When the electro-magnet is energized the armature 91 is drawn down and releases the latch 86, whereupon the wheel 76 may be driven by the arrangement which has heretofore been described, and as the wheel 76 turns it will cause the gear 74 to turn, and thereby cause through the mechanism for operating the shaft 54, the said shaft 54 to be reciprocated. As will later be described, the arrangement of the parts is such that the latch 86 will be released practically as soon as it has been withdrawn from the detent in the gear 74, so that it will be in position to engage the detent in the gear 74 as soon as that gear has made one revolution.

This one revolution of the gear 74 would be represented by a complete reciprocation of the shaft 54 from the position shown in Fig. 4 back to the position where it has moved beyond the hopper 60, engaged a new printing impression member dropped down in front of it and moved again to the position shown in Fig. 4.

The electromagnet 92 is operated through the instrumentality of an electric circuit, which includes the electromagnet 92 and a suitable source of current, and a terminal carried by 92 and a suitable source of current, and a terminal of the circuit is carried by a plate 93 which is shown in Fig. 7. This plate is carried by the channel member 24

and is insulated from the channel member. The other terminal of the circuit is formed by the links 23 which comprise the chain carrying printing plates that form a part of the printing instrumentality A. One of these plates, which we will designate 23^a, carries a contact member 23^b. This contact member when it comes upon the plate 93 completes the circuit through the electro-magnet 92 and causes the armature 91 to be attracted toward the electro-magnet and thus sets in motion the various instrumentalities which have heretofore been described for causing a reciprocation of the shaft 54.

It will be obvious that shaft 54 will be reciprocated only after a predetermined number of the links 23 have imparted their impression upon the material being printed and the same printed matter carried by the links will be repeated, but there will be a change in the printed matter which will occur in impressions on the strip being printed in each series of slips as the printing member 23 is changed. It will thus be seen in the machine under discussion that one aspect of the machine presents one printing mechanism in which each successive impression of the printing mechanism is different than the preceding one, and another printing mechanism in which the printed impression or a part of the printed impression is changed at predetermined intervals with respect to the printing accomplished by the first mechanism.

The material upon which the impressions from the printing instrumentalities are printed is indicated at 100, and may be fed from any suitable source. In the particular machine which is herein disclosed the paper fed in is in folded condition and it will be apparent from the description of the machine which has heretofore been given that the printing by the printing instrumentality A, that is to say, the one having the traveling links, will print on one side of the strip 100, while the printing instrumentality C will print on the opposite or lower side of the folded strip, and as explained at the first of the specification.

At 5 there are represented a pair of rolls 115 which engage the strip of paper 100 being printed upon to draw it through the machine and through the printing mechanisms which have been referred to and which will be subsequently described. After passing through the rolls 5 the paper passes beneath a retaining member and comes in the path of a revolving knife 7. The knife coöperates with a platform 8 lying beneath the retaining member 6 and the knife 7 and the end of the platform 8 constitute a pair of shears which sever the paper. At the time of the severing of the strip of paper the paper will be temporarily retarded and tend to buckle. Such buckling as may occur may be beneath 130

the member 6 and as this member is made to be slightly resilient, the buckle will be removed from the strip as soon as the severing is completed, by the passage of the slip between the member 6 and the platform 8.

Right at the end of the platform 8 there is a receptacle 9 which at its lower end forms a trough, as indicated at 10, this receptacle 9 being adapted to receive the slips as they are severed and the trough to convey the slips away from the machine to a point at which they may be conveniently removed and handled. The upper part of the chute 9 is provided with slots 11 in one wall thereof and slots 12 thereof in an opposite wall, the slots 11 and 12 being in alinement. Extending through the slots 11 is a wire loop 13. This loop has a head portion 13^a and the ends of the loop are suitably secured in a rotatable member, as indicated at 14. This rotatable member is spring retained, as indicated at 15 in Fig. 3 so that when the wire loop is depressed the spring 15 will tend to return it to its initial position. Carried by a rotatable member 7^a, which carries the knife 7, is an outwardly extending post 16. This carries two arms 17 and these arms are adapted to move through the slots 12, engage the head 13^a of the spring loop 13 and depress it. These arms 17 are so arranged with respect to the knife that they will be bearing upon the loop 13 to depress it at just the time that the severed slip is ready to descend in the receptacle 9, and the spring loop engaging the slip will forcefully push it into the receptacle thus removing any chance of the slip flying out and not being properly placed in the receptacle.

The loop 13 descends sufficiently far in the receptacle 9 to push the slip beneath the spring arms 9^a which are mounted at opposite sides of the chute and have portions extending within the chute.

In the machine here shown and described there are two sets of links shown, together with two drums corresponding to the drum 20, upon which link printing chains may be supported. Both of these drums 20 and 20^a are adapted to be moved sidewise so that while one chain of links 22 is being employed in the printing operation a second set of printing links may be made. For instance, the links coöperating with the drum 20^a may be in preparation while links coöperating with drum 20 are printing and when the run with the links on the drum 20 has been completed the links coöperating with the drum 20^a may be pushed over into operative position and the links coöperating with the drum 20 pushed out of operative position, and the links coöperating with the drum 20 may be changed to make up a new printing set while the links coöperating with the drum 20^a are printing.

This may be accomplished by mounting

the drums 20 and 20^a upon the shaft 21 in such a manner that they will be in driving relationship to the shaft 21 when they are in position to print, and out of driving relationship when they are not in position to print. Furthermore, it will be necessary to move the upper channel members 24 and the lower channel members 25 and the channel members which hold the links of the printing chain coöperating with the drum 20^a. As one means for accomplishing this I may use arms such as shown at 101, 102, which are connected with the lower channel members supporting the printing chains and with the drums 20 and 20^a. These arms or members 101, 102, are formed with racks at their outer ends as illustrated at 102^a, and coöperating with the racks are gears illustrated at 103. The gears are carried upon a shaft 104 which may be operated by a handle 105. It will be understood that there will be a plurality of such arms as illustrated at 101 and 102, extending throughout the length of the machine and coöperating with the lower channel members which support the printing chain. Each of these arms will coöperate with a gear such as shown at 103, which will be carried upon the shaft 104, so that all the gears upon this shaft may be simultaneously operated and thus effectually cause the side movement of the drums 20 and 20^a as well as the channels which support the printing chain associated with each drum.

The particular slip which is printed by the machine organized as heretofore described is shown in Figs. 10, 11, 12. One side of the folded slip in enlarged form is shown in Fig. 11, while the reverse side of the slip is shown in Fig. 12. The slip unfolded and with the printed matter on is shown in Fig. 10. The particular slip with its many folds herein described is not at all essential to the operation of the machine which has heretofore been described, but as these slips when printed must meet the requirements of the post office department, we have shown such a slip as is required by them. So far as the printing is concerned, however, it occupies only the portions of the slip which are shown in the drawing.

The matter which is shown as printed upon the slip in Fig. 11, embodies the variable matter and a part of the constant matter, that is to say, the lines "Omaha and Ogden T R 13, and Iowa No. 3 via Chicago" would only occur upon one slip in a series of slips bearing a given date. Each other slip in the series of the same date would have different printing matter, making up these two lines either in part or in whole. The line "from L. S. & M. S. T R 2" would be constant for each slip throughout a run of slips, for it represents the source from which the postal clerk is making up his pouches.

Obviously that which is printed on the re-

verse side of the slip, as shown in Fig. 12, would be constant, so far as the name is concerned, and so far as the date is concerned, until all the slips for a given date had been 5 made up. Then of course, it would be necessary to make up the same slips for another date.

It will be seen that the number of links in the printing chain may be as few or as many 10 as is desirable, so that a complete run of as many or as few slips may be made up as is desirable.

Furthermore, the particular run of a postal clerk may be made up for a number of 15 dates in advance for each postal clerk knows at least within limits just on what days he will make his runs and just what sacks he will be required to prepare.

It will be apparent from the description 20 of the machine that there will be a link in the printing chain prepared for each sack which must be made up by the postal clerk, and when this printing chain has printed all 25 the links once for a given date one run will have been completed. It will then be in order to change the date and run a second series of slips with the new date and so on, running each series of slips with a different date.

30 This changing of the date is automatically accomplished in the machine by causing the operation of the electro-magnet 92 at the end of each complete run of the printing chain, and as explained, this operation of the electro-magnet is accomplished by closing a circuit of which the electro-magnet is a part, and the closing of the circuit is accomplished by the contact 23^b carried by a link of the printing chain, which 35 at each complete run of the printing chain 40 contacts with the plate 93, and this closes the circuit through the electro-magnet 92.

It will readily be seen that while the particular strip of material to be printed on 45 is supplied in folded condition, and that one printing instrumentality prints on the upper side while a second printing instrumentality prints on the lower side of the slip, that these particular arrangements are 50 merely to serve the purpose of printing what I term a postal slip, and that it is perfectly possible to organize the machine without departing from my invention so 55 that it will print all the matter upon the upper side of the strip. Furthermore, while the machine is organized so that the shaft 54 operates to periodically change the printing member which prints different dates, that there is no limitation in this 60 to the printing of date only, as other matter might be printed by the printing element 63.

The mechanism by which the various printing instrumentalities are operated is 65 so organized that the printing instrumen-

talities print upon the impression receiving strip in a predetermined relationship, and while they each print independently, the impression of each, for a given slip, is in registry with the impressions of the others, 70 the same as if the matter on each slip had been printed from a single form.

Having thus described my invention, what I claim is:

1. In a printing machine for printing a 75 series of slips, the printed matter being in part constant upon all of the slips and in part varying upon each successive slip, a plurality of links which are pivoted to each other, printing characters carried by each 80 link the characters of each link differing from the characters on the others, a platen with which each link in turn co-operates, a second printing instrumentality consisting of an impression member and a platen, 85 means for supplying a strip of impression receiving material to the links and their platen and the second printing instrumentality in succession, means severing the strip into slips after they are printed upon, 90 and means for operating the printing mechanisms in harmony, the impressions of the printing mechanism registering when printed upon the impression receiving material. 95

2. A printing machine for printing a series of slips, the printed matter being in part constant upon all of the slips and in part varying upon each successive slip, comprising a plurality of links which are pivoted to each other, printing characters carried by each link, the characters of each link differing from that of the characters of the others, a rotatable drum around which the chain of links passes, a platen 105 with which each link in turn co-operates, a second instrumentality consisting of an impression member and a platen, means for supplying a strip of impression receiving material to pass between the links and their 110 platen and to the second printing instrumentality in succession, means for severing the strip into slips after it has been printed upon, the impressions of the printing mechanisms registering when printed upon 115 by the impression receiving material.

3. A printing machine for printing a series of slips, the printed matter being in part constant upon all the slips and in part varying upon the successive slips, comprising a frame supporting a pair of rotatable drums, a plurality of links which are pivoted to each other thereby forming a chain which extends around said drums, printing characters carried by each of the links, the 120 arrangements of each of the links differing from the characters of the others, a platen with which each link co-operates, a second printing instrumentality consisting of an impression member and a platen, means for supplying a strip of impression receiving material to pass between the links and their platen and to the second printing instrumentality, 125 means for severing the strip into slips after it has been printed upon, the impressions of the printing mechanisms registering when printed upon by the impression receiving material.

plying a continuous strip of impression receiving material to pass between the chain and its platen and to the second printing instrumentality in succession, 5 means for severing said strip into slips after printing, mechanism operating the impression member in harmony, the impressions of the printing mechanism registering when printing upon the impression receiving material.

4. A printing machine for printing a series of slips, the printed matter being in part constant upon all of the slips and in part varying upon each successive slip, comprising 15 an impression member and a platen co-operating therewith, a second printing mechanism comprising two parallel printing chains each composed of a plurality of links which are pivoted to each other, printing 20 characters carried by each link, means for moving the said parallel printing chains, means for moving either one of said printing chains in alinement with the first mentioned impression member and platen, a platen with 25 which each of the links in the printing chain which is in alinement with the impression member and its platen may in turn coöperate, means for supplying impression material to the printing chain in operating position and 30 its platen and to the first mentioned impression member and its platen in succession, means for operating the printing mechanisms in harmony, the impressions of the 35 printing mechanisms registering when printed upon the impression receiving material.

5. A printing machine comprising a series of links which are pivotally connected to each other, each of said links serving as a form carrier, printing characters carried 40 by each link form, means for supporting the chain of links and for moving the same, a platen with which each link in turn coöperates, means for supplying impression receiving material between the links of the chain 45 and the platen, a second printing chain, comprising links of the same character of the first mentioned links, means for supporting the said second set of links and for moving the same, a common support for both printing 50 chains and means for moving said support to bring either one of said printing chains into printing relationship.

6. A printing machine for printing a series of slips, the printed matter being in part 55 constant upon all the slips and in part varying upon each successive slip, comprising a printing mechanism having an impression member, which comprises a plurality of groups of printing characters, the printing 60 characters of each group being different from the characters of the others, a platen with which each of the groups of characters in turn coöperates, a second printing instrumentality consisting of an impression member and a platen, means for holding a new

impression member to be used and means for removing a used impression member and replacing it with another impression member at predetermined intervals in the operation of the machine, means for supplying impression receiving material to the first printing instrumentality and to the second printing instrumentality in succession, means for operating the printing mechanisms in harmony, the impressions of the printing mechanisms registering when printed upon the impression receiving material.

7. A printing machine for printing a series of slips, the printed matter being in part constant upon all the slips and in part varying upon each successive slip, comprising a printing mechanism having an impression member, which comprises a plurality of groups of printing characters; the printing characters of each group being different from the characters of the others, a platen with which each of the groups of characters in turn coöperates, a second printing instrumentality, comprising a reciprocating support, an impression member carried by said support, a platen with which said impression member coöperates, means for reciprocating the support at predetermined intervals in the operation of the printing machine, the said impression member being removed as 90 the said support reciprocates, means for supplying a new impression member and causing the same to be moved into the path of movement of said reciprocating support and to be engaged by said support, thereby moving the new impression member into printing position, means for supplying impression receiving material to the links and their platen and to the second printing instrumentality in succession, means for operating the 105 printing mechanisms in harmony, the impressions of the printing mechanism registering when printing upon the impression receiving material.

8. A printing machine for printing a series of slips, the printed matter being in part constant upon all the slips and in part varying upon each successive slip, comprising a printing mechanism having an impression member, which comprises a plurality of groups of printing characters, the printing characters of each group being different from the characters of the others, a platen with which each of the groups of characters in turn coöperates, a second printing instrumentality comprising a driven shaft and fixed impression member carried by said shaft, a reciprocating shaft in alinement with the driven shaft, a removable impression member carried by said reciprocating 120 shaft, means for reciprocating said shaft at predetermined intervals in the operation of the printing machine, the removable impression member being removed from the reciprocating shaft as it reciprocates, means 130

for supplying a new impression member to the shaft, the said shaft moving the new impression member to printing position, stops carried by said impression members 5 whereby the fixed impression member will engage the assembly impression member and cause it to turn as the fixed shaft is operated, means for supplying impression material to the first printing instrumentality and 10 to the second printing instrumentality in succession, means for operating the printing mechanisms in harmony, the impressions of the printing mechanisms registering when printed upon the impression receiving material. 15

9. A printing machine for printing a series of slips, the printed matter being in part constant upon all the slips and in part varying upon each successive slip, comprising a 20 printing mechanism having an impression member, which comprises a plurality of groups of printing characters, the printing characters of each group being different from the characters of the others, a platen 25 with which each of the groups of characters in turn coöperates, a second printing instrumentality consisting of an impression member and a platen, a support upon which said impression member is removably carried, means for moving the said supporting member at predetermined intervals in the operation of the machine, whereby the impression member carried thereby is removed, means for supplying a new impression member, 30 the said movable support engaging with a new impression member after the support has discharged its first mentioned impression member, the support then moving the impression member thus engaged in printing position, means for preventing the new impression member from falling off the support as the support moves said impression member into printing position, means for supplying impression receiving material to 35 the first mentioned printing instrumentality and to the second printing instrumentality in succession, means for operating the printing mechanisms in harmony, the impressions of the printing mechanisms registering when printed upon the impression receiving material. 40

10. A printing machine for printing a series of slips, the printed matter being in part constant upon all the slips and in part varying upon each successive slip, comprising a 45 printing mechanism having an impression member, which comprises a plurality of groups of printing characters, the printing characters of each group being different from the characters of the others, a platen 50 with which each of the groups of characters in turn coöperates, a second printing instrumentality consisting of an impression member and a platen, a support upon which the said impression member is removably carried,

ried, means for moving the said supporting member at predetermined intervals in the operation of the machine, whereby the impression member carried thereby is removed, means for supplying a new impression member, 70 the said movable support engaging with the said new impression member after the said support has discharged the first mentioned impression member, the support then moving the impression member thus engaged 75 into printing position, a member moving with the reciprocating shaft, said member engaging with the impression member carried thereby through a portion of the travel of the reciprocating shaft for the purpose 80 of preventing the impression member from leaving said shaft, means for supplying impression receiving material to the first mentioned printing instrumentality and to the second printing instrumentality in succession, means for operating the printing mechanisms in harmony, the impressions of the printing mechanisms registering when printed upon the impression receiving material. 85

11. A printing machine for printing a series of slips, the printed matter being in part constant upon all the slips and in part varying upon each successive slip, comprising a plurality of links which are pivoted to each other, printing characters carried 90 by each link, the characters of each link differing from the characters of the others, a platen with which each link in turn co- 95 operates, a second printing instrumentality consisting of an impression member and a platen, means for holding a new impression member to be used and means for removing a used impression member and replacing it with another impression member at predetermined intervals in the operation of the 100 machine, means for supplying impression receiving material to the links and their platen and to the second printing instrumentality in succession, means for operating the printing mechanisms in harmony, 105 the impressions of the printing mechanisms registering when printed upon the impression receiving material. 110

12. A printing mechanism for printing a series of slips, the printed matter being in 115 part constant upon all the slips and in part varying upon each successive slip, comprising a plurality of links which are pivoted to each other, printing characters carried upon each link, the characters of each link 120 differing from the characters of the others, a platen with which each link coöperates, a second printing instrumentality consisting of an impression member and a platen, a support upon which the said impression member is removably carried, means for moving the said supporting member at predetermined intervals in the operation of the machine, whereby the impression member carried thereby is removed, means for hold- 125 130

ing a plurality of impression members, the said movable support engaging with one of said impression members from the supply after the said support has discharged the 5 first mentioned impression member, the support then moving the impression member thus engaged into printing position, means for supplying impression receiving material to the links and their platen and to the sec- 10 ond printing instrumentality in succession, means for operating the printing mechanisms in harmony, the impressions of the printing mechanisms registering when printed upon the impression receiving material.

15 13. A printing machine for printing a series of slips, the printed matter being in part constant upon the slips and in part varying upon each successive slip, comprising a plurality of links which are pivoted 20 to each other, printing characters carried by each link, the characters of each link differing from the characters of the others, a platen which each link in turn coöperates, a second printing instrumentality comprising a reciprocating shaft, an impression member carried by said shaft, a platen with which said impression member coöperates, means for reciprocating the shaft at predetermined intervals in the operation of the 25 printing machine, the said impression member being removed from the shaft as the said shaft reciprocates, means for supplying a new impression member and causing the same to move into the path of movement of the said reciprocating shaft and to be engaged by said shaft thereby to move the new impression member into printing position, means for supplying impression receiving material to the links and their platen 30 and to the second printing instrumentality in succession, means for operating the printing mechanisms in harmony, the impressions of the printing mechanisms registering when printed upon the impression receiving material.

40 14. A printing machine for printing a series of slips, the printed matter being in part constant upon all the slips and in part varying upon each successive slip, comprising a plurality of links which are pivoted to each other, printing characters carried by each link, the characters of each link differing from the characters of the others, a platen with which each link in turn coöperates, a second printing instrumentality comprising a fixed impression member and a removable impression member, a platen with which said impression members coöperate, means for removing the removable impression member and replacing it with a new impression member at predetermined periods in the operation of the printing machine, means for supplying impression receiving material to the links and their platen 45 and to the second printing instrumentality

in succession, means for operating the printing mechanisms in harmony, the impressions of the printing mechanisms registering when printed upon the impression receiving material.

15. A printing machine for printing a series of slips, the printed matter being in part constant upon all the slips and in part varying upon each successive slip, comprising a plurality of links which are pivoted to each other, the printing characters carried by each link, the characters of each link differing from the characters of the others, a platen with which each link in turn coöperates, a second printing instrumentality comprising a driven shaft, a fixed impression member carried by said shaft, a reciprocating shaft in alinement with the driven shaft, a removable impression member carried by said reciprocating shaft, means for reciprocating said shaft at predetermined intervals in the operation of the printing machine, the removable impression member being removed from the shaft as it reciprocates, means for supplying a new impression member to the shaft, the shaft moving the new impression member to printing position, stops carried by the said impression members whereby the fixed impression member will engage the removable impression member and cause it to turn as the fixed shaft is turned, means for supplying impression material to the links and their platen and to the second printing instrumentality in succession, means for operating the printing mechanisms in harmony, the impressions of the printing mechanisms registering when printed upon the impression receiving material.

16. A printing mechanism for printing a series of slips, the printed matter being in part constant upon all the slips and in part varying upon each successive slip, comprising a plurality of links which are pivoted to each other, printing characters carried upon each link, the characters of each link differing from the characters of the others, a platen with which each link operates, a second printing instrumentality consisting of an impression member and a platen, a support upon which said impression member is removably carried, means for moving the said supporting member at predetermined intervals in the operation of the machine whereby the impression member carried thereby is removed, means for supplying a new impression member, said removable support engaging with said new impression member after the said support has discharged the first mentioned impression member, the support then moving the impression member thus engaged into printing position, means for moving with the said movable support during a portion of its movement to prevent an impression member from falling off the said

movable support as it moves to printing position.

17. A printing machine for printing a series of slips, the printed matter being in part 5 constant upon all the slips and in part varying upon each successive slip, comprising a printing mechanism having an impression member, which comprises a plurality of groups of printing characters, the printing 10 characters of each group being different from the characters of the others, a platen with which of the groups of characters in turn coöperates, a second printing instrumentality comprising a reciprocating shaft, 15 an impression member carried by said shaft, a platen with which said impression member cooperates, means for reciprocating the shaft at predetermined intervals in the operation of the printing machine, said impression 20 member being removed from the shaft as said shaft reciprocates, means for supplying a new impression member and causing the same to move into the path of movement of said reciprocating shaft and to be engaged 25 by said shaft thereby to move the new impression member into printing position, means for moving with the reciprocating shaft adapted to engage an impression member carried by said shaft to prevent the same 30 from falling off the shaft as the shaft moves, means for supplying impression receiving material to the first mentioned printing instrumentality and to the second printing instrumentality in succession, means for operating 35 the printing mechanisms registering when printed upon the impression receiving material.

18. A printing machine for printing a series of slips, the printed matter being in part 40 constant upon the slips and in part varying upon each successive slip, comprising a plurality of links which are pivoted to each other, printing characters carried by each link, the characters of each link differing 45 from the characters of the others, a platen with which each link in turn operates, a second instrumentality comprising a reciprocating shaft, an impression member carried by said shaft, a platen with which said impression 50 member coöperates, means for reciprocating the shaft at predetermined intervals in the operation of the printing machine, said impression member being removed from the shaft as said shaft reciprocates, means for 55 supplying a new impression member and causing the same to move into the path of movement of said reciprocating shaft and to be engaged by said shaft thereby to move the new impression member into 60 printing position, means for moving with the reciprocating shaft adapted to engage an impression member carried by said shaft to prevent the same from falling off the shaft as the shaft moves, means for 65 supplying impression receiving material to

the first mentioned printing instrumentality and to the second printing instrumentality in succession, means for operating the printing mechanisms registering when printed upon the impression receiving material. 70

19. A printing machine for printing a series of slips, the printed matter being in part constant upon all the slips and in part varying upon each successive slip, comprising a printing mechanism having an impression member, which comprises a plurality of groups of printing characters, the printing characters of each group being different from the characters of the others, a platen with which each of the groups of characters 80 in turn coöperates, a second instrumentality comprising a fixed impression member and a removable impression member, a platen with which said impression member coöperates, means for removing the removable impression member and replacing it with a new impression member at predetermined periods in the operation of the printing machine, means engaging the removable impression member for preventing it falling 85 off its supporting means, means for supplying impression receiving material to the links and their platen and to the second instrumentality in succession, means for operating the printing mechanisms in harmony, the impressions of the printing mechanisms registering when printed upon the impression receiving material. 90

20. A printing machine for printing a series of slips, the printed matter being in part constant upon all the slips and in part varying upon each successive slip, comprising a printing mechanism having an impression member, which comprises a plurality of groups of printing characters, the printing characters of each group being different from the characters of the others, a platen with which each of the groups of characters in turn coöperates, a second printing instrumentality comprising a driven 105 shaft and fixed impression member carried by said shaft, a reciprocating shaft in alignment with the driven shaft, a removable impression member carried by said reciprocating shaft, means for reciprocating said shaft 110 at predetermined intervals in the operation of the printing machine, the removable impression member being removed from the shaft as it reciprocates, means for supplying a new impression member to the shaft, 115 the said shaft moving the new impression member to printing position, a movable retaining member extending through the said fixed shaft, but not turning therewith, said retaining member engaging the impression 120 member carried upon the reciprocating member engaging the impression member carried upon the reciprocating shaft, means for moving the said retaining member with the reciprocating shaft to a portion of its 125 130

movement, the retaining member preventing the impression member carried upon the reciprocating shaft from dropping off the same, means for supplying impression material to the first mentioned printing instrumentality and to the second printing instrumentality in succession, means for operating the printing mechanisms in harmony, the impressions of the printing mechanisms 10 registering when printed upon the impression receiving material.

21. A printing machine for printing a series of slips, the printed matter being in part constant upon all the slips and in part 15 varying upon each successive slip, comprising a printing mechanism having an impression member, which comprises a plurality of groups of printing characters, the printing characters of each group being 20 different from the characters of the others, a platen with which each of the groups of characters in turn coöperates, a second printing instrumentality comprising a driven shaft and fixed impression member carried 25 by said shaft, a reciprocating shaft in alinement with the driven shaft, a removable impression member carried by said reciprocating shaft, means for reciprocating said shaft at predetermined intervals 30 in the operation of the printing machine, the removable impression member being removed from the shaft as it reciprocates, means for supplying a new impression member to the shaft, the said shaft moving the new impression member to printing position, a movable retaining member 35 extending through the said fixed shaft but not turning therewith, said retaining member engaging the impression member carried upon the reciprocating shaft, means for moving the said retaining member with the reciprocating shaft to a portion of its movement, the retaining member preventing the impression member carried upon the reciprocating shaft from dropping off the same, stops carried by the said impression members whereby the fixed impression member 45 will engage the removable impression member and cause it to turn as the fixed shaft is turned, means for supplying impression material to the first mentioned printing instrumentality and to the second printing instrumentality in succession, means for operating the printing mechanisms in harmony, the impressions of the printing mechanisms 50 registering when printed upon the impression receiving material.

22. A printing machine of the character described, comprising a reciprocating shaft, 60 an impression member carried by said shaft, a platen with which the impression member coöperates, means for reciprocating said shaft at predetermined intervals, means for removing the impression member from the shaft as the shaft is reciprocated, means for

supplying a new impression member to the shaft during its reciprocation, the shaft moving the new impression member to printing position and means for preventing the said impression member from dropping off 70 the said shaft as it reciprocates.

23. A printing machine of the character described comprising a reciprocating supporting member, an impression member carried by said supporting member, a platen 75 with which the impression member co-operates when in printing position, means for moving said supporting member at predetermined intervals, means extraneous of the supporting member which engages and 80 receives the impression member from the supporting member as the supporting member is moved, means for supplying a new impression member to the supporting member during its movement the said supporting member moving the new impression member to printing position.

24. A printing machine of the character described comprising a reciprocating supporting member, an impression member carried by said supporting member, a platen 90 with which the impression member co-operates when in printing position, means for moving said supporting member at predetermined intervals, means for removing 95 an impression member from the supporting member as the said supporting member is moved, means for supplying a new impression member to the supporting member after the old impression member is removed the 100 said supporting member moving the new impression member to printing position.

25. A printing machine of the character described, comprising a reciprocating shaft, an impression member carried by said shaft, 105 a platen with which the impression member coöperates, means for reciprocating said shaft at predetermined intervals, means for removing the impression member from the shaft as the shaft is reciprocated, means for 110 supplying a new impression member to the shaft during its reciprocation, the shaft moving the new impression member to the printing position.

26. A printing machine of the character 115 described, comprising a reciprocating shaft, an impression member having an opening through which the reciprocating shaft extends, a platen coöperating with the impression member, means for reciprocating the 120 shaft, means for removing the impression member from the shaft as the shaft reciprocates, means for supplying a new impression member to the shaft during its reciprocation and moving the new impression member into 125 position.

27. A printing machine of the character described, comprising a reciprocating shaft, an impression member provided with an opening into which the reciprocating shaft 130

extends, a platen coöperating with the impression member, means for reciprocating the shaft, means for removing the impression member from the shaft as the shaft 5 reciprocates, a magazine for holding other impression members, means for retaining the impression members in said magazine, the last mentioned means being operated to release a new impression member, means for 10 operating the retaining means during the reciprocation of the shaft and permitting a new impression member to move in front of the reciprocating shaft whereby said shaft engages with the opening in said impression 15 member and moves it forward to the printed position.

28. A printing machine of the character described, comprising a driven shaft and fixed impression member carried by said 20 shaft, a reciprocating shaft in line with the fixed shaft, a removable impression member carried by said shaft, a platen with which the impression members coöperate, means for reciprocating the reciprocating shaft at 25 predetermined intervals, means for removing the removable impression member when the reciprocating shaft is reciprocated, means for supplying a new impression member to said reciprocating shaft, the said reciprocating shaft moving the new impression 30 member into printing position, a retaining member extending through the fixed shaft, but not turning therewith, said retaining member engaging the impression member carried by the reciprocating shaft and moving with the reciprocating shaft through a part of its reciprocation, the retaining member preventing the impression member carried by said shaft from dropping 35 off the shaft.

29. A printing machine of the character described, comprising a driven shaft which is hollow, a fixed impression member carried by said shaft, a rod extending through 45 the hollow driven shaft, a spring normally urging said rod through the driven shaft, a stop member carried by said rod to limit the movement of the rod through the said hollow shaft, a head carried by the rod, a reciprocating shaft in line with the fixed 50 shaft and coöperating with the head upon the rod, a removable impression member carried by the said reciprocating shaft which is engaged by the head upon the rod, a platen with which the said impression 55 members coöperate, means for reciprocating the reciprocating shaft at predetermined intervals, means for removing the removable impression member when the reciprocating 60 shaft is reciprocated, a magazine for holding their impression members, means for permitting a new impression member to move in front of the reciprocating shaft during the reciprocation of said shaft there-

by moving the new impression member into 65 position, stop members carried by said impression members, said stop members engaging when the driven shaft is rotated, whereby these stops on the said impression members engage and the removable impression member is rotated. 70

30. A printing machine of the character described, comprising a driven shaft, a fixed impression member carried by said shaft, a reciprocating shaft in line with the fixed 75 shaft, removable impression members carried by said shaft, a platen with which the impression members coöperate, means for reciprocating the reciprocating shaft at predetermined intervals, means for removing 80 the removable impression member when the reciprocating shaft is reciprocated, a magazine for holding other impression members, means for permitting a new impression member to move in front of the reciprocating 85 shaft during reciprocation of said shaft thereby moving the new impression member into position, stop members carried by the said impression members, said stop members engaging when the driven shaft is rotated 90 whereby the stops on the said impression members engage and the removable impression member is rotated.

31. A printing machine for printing a series of slips, the printed matter being in 95 part constant upon all the slips and in part varying upon each successive slip, comprising a plurality of links which are pivoted to each other, printing characters carried by each link, the characters of each link differing from the characters of the others, a platen with which each link coöperates, a second printing instrumentality consisting of an impression member and its platen, means for supplying a strip of impression 100 receiving material to the links and their platen and to the second printing instrumentality in succession, means for operating the printing mechanism in harmony, the impressions of the mechanisms registering 105 when printed upon the strip of impression receiving material, means for severing the strip of impression receiving material at points between the printed impressions thereon, a receptacle for receiving the slips 110 when severed and means for engaging the slip and pushing it into the said receptacle after it is severed.

32. A printing machine for printing a series of slips, the printed matter being in 120 part constant upon all of the slips and in part varying upon each successive slip, comprising an impression member and a platen with which the impression member coöperates, means for supplying a strip of impression receiving material to pass between the impression member and the platen, means for severing the strip into predetermined 125

lengths, a receptacle for holding the slips after being severed, a spring retained member adapted to engage each slip as it passes to the receptacle, a rotatable arm for engaging with the said spring held member for moving it, an arm within the receptacle

adapted to engage and hold the slip after it has been passed beneath the same by the said spring held member.

In testimony whereof I hereunto affix my ¹⁰ signature in the presence of two witnesses.

GEORGE L. FULK.
